UNITED STATES PATENT OFFICE.

ELMER E. E. SUTPHIN, OF DAVENPORT, IOWA.

EXPLOSIVE-ENGINE.

1,071,823.

Specification of Letters Patent.

Patented Sept. 2, 1913.

Application filed July 26, 1912. Serial No. 711,699.

To all whom it may concern:

Be it known that I, ELMER E. E. SUTPHIN, of Davenport, in the county of Scott and State of Iowa, have invented certain new and useful Improvements in Explosive-Engines; and I hereby declare that the following is a full, clear, and exact description thereof, reference being had to the accompanying drawings, which form part of this specification.

This invention is a novel improvement in explosive engines of the rotary type in which the gases are ignited in an explosion chamber, or chambers, from which they are admitted into the working chamber wherein is preferably mounted a rotor, or turbine wheel, to which motion is imparted by such gases and after the latter have been used in said chamber they may be exhausted to the atmosphere or otherwise utilized.

The principal feature of my invention is the novel combination of an explosive chamber, a working chamber, and means for producing and conducting explosive gases from such explosion chamber to the working chamber.

Subordinate features are (1) novel means whereby the gases may be caused to drive the rotor in either direction desired; (2) novel means for operating the cylinders in the explosive chambers; (3) novel means for operating the valves; (4) and the general novel arrangement and construction of the engine as a whole.

I will explain the invention in detail with reference to the accompanying drawings which illustrate one form of the engine embodying the invention and which in connection with the following description will enable any one skilled in the art to construct and use the same.

In the drawings Figure 1 is a plan view of the complete engine. Fig. 2 is a transverse sectional view thereof. Fig. 3 is a cross section on the dotted lines 28—29 of Fig. 2. Fig. 4 is a plan view of one-half of the outer shell 15 of the rotor. Fig. 5 is a cross section on the dotted line 30—31—32 of Fig. 2. Fig. 6 is a plan view of the arrangement of the wiring for the ignition for combustion of the gases. Fig. 7 is a cross section of the intake valve K, Fig. 1. Fig. 8 is a vertical section of Fig. 7 on the dotted line 39—40 Fig. 7. Fig. 9 is a cross section of the valve M, Fig. 2 on the dotted line 33—38, Fig. 5. Fig. 10 is

an enlarged perspective view of one corner, or part of the engine showing the general operative arrangement of the cylinders and controlling valves, parts being broken away for clearness of illustration.

As shown the engine comprises a main frame or casting A which is shown as approximately rectangular and has a central cylindric working chamber which may be closed at its ends by removable plates D and in which are bearings for a main shaft a which extends axially through said chamber; within this working chamber rigidly secured to the axle in any suitable way is a rotor 21 which may consist of a cylindric body provided with radially disposed transverse blades 13 forming pockets 3 into which the propelling gases are injected as herein-after described. The plates D, Fig. 3, are preferably made hollow and provided with water chambers 17 to which water can be supplied through openings h, Figs. 3 and 10, by any suitable pipe connection (not shown); and the plates are provided with apertures h' near their axes through which water can pass through apertures 18 in the sides of the rotor 21 into the water chamber 2 in said rotor, see Figs. 2 and 3; and the water can escape at the opposite side of the rotor through the apertures 18' and h' to the outlet h² at the opposite side of the casting; thus a circulation of water can be maintained around the working chamber and within and through the rotor therein.

As shown the rotor is impelled by explosive gases which are supplied thereto through suitable valve ports from the explosion chambers, four of which are shown,—such exploding chambers (34, 35, 36 and 37) being in cylinders B, B', B², B³, attached to the frame. The exploding chambers and their valve connections and parts are substantially alike, and preferably the exploding chambers are cylindric in cross section, and in each exploding chamber is a cylinder piston which is operated by the gases as hereinafter described.

One end of each cylinder communicates by a port 5 with an adjacent valve chamber in the casing, in which is a rocking valve M² and the other end of each cylinder communicates with the adjacent valve chamber by means of a port 5'. As shown there is one valve chamber adjacent the adjacent ends of each pair of cylinders, or in other words there are four valves M² for four cylinders;

each valve M^2 is provided with two ports 6, 6', either of which may be brought into communication with either port 5 or 5'; and each valve chamber communicates with the periphery of the working chamber by ports 7 and 7', port 7 leading to the left and ports 7' to the right. The ports in valves M^2 are so proportioned that when ports 6 are in communication with ports 5 or 5', the gases 10 will be admitted from the cylinders through the valve chambers to the ports 7, and the rotor will thus be turned to the left, Fig. 2. But if the valves be shifted so that the ports 6' register with the ports 5 or 5' then 15 ports 7 will be closed and the gases will be admitted through the ports 7' to the working chamber, and the rotor will be driven to the right. Thus by properly setting the valves M^2 the rotor can be caused to turn to 20 the right, or to the left. The mechanism for adjusting the valves to reverse the engine is hereinafter described.

Adjacent each valve M^2 and intermediate the outer ends of each pair of adjacent cylinders, is a rock shaft H which is mounted 25 in a bracket I attached to the frame A. On this shaft is a crank arm G which is pivotally connected by loose pivots to rods F, F'. Rod F enters the head of one of the adjacent cylinders and rod F' enters the head of the other adjacent cylinder (see Fig. 10); and these rods project sufficiently into the cylinder to be struck by the pistons 30 therein when the piston moves to that end of the cylinder, and when either rod is struck by a piston it will impart a rocking motion to the shaft H.

Referring to Figs. 2 and 10, if the piston 4' in chamber 36 be driven to the left hand 40 end of the upper cylinder B² the piston 4' will strike the rod F and force it to the left, thereby rocking shaft H to the left, and causing the rod F' to be projected farther into the chamber 35. When piston 4 in 45 chamber 35 is driven toward rod F' it will force the latter outward and shaft H will be rocked to the right and rod F will be again projected into the left hand end of chamber 36. The pistons in the chambers 50 36 and 35 are operated in alternation, so that the shafts H are rocked first one way and then the other; and the same is true of each rock shaft H of the engine shown.

On each shaft H is a crank disk N which 55 may be connected by a toggle link Q-R to a slotted head M' on the end of the adjacent valve M^2 . As shown the link R is adjustably connected (as by a pin k and slot l) to the head M of the valve M^2 . This 60 slot l in the head M of the valve M^2 is for the purpose of adjusting the valve so that the ports 6-6' will register with the ports 5-5'. The slot l only acts as the crank of the valve M^2 and does not necessarily extend 65 across the center of valve M^2 it is not

used in any way for the purpose of reversing the rotor, but is to be used in case some of the ports 5-5' should be a little closer together or farther apart than the others, the link R could then be adjusted in the slot l so as to give the valve more or less throw as the case should demand. The reversing of the rotor is accomplished entirely by throwing the links Q, R, to the position indicated by the dotted lines, this 70 brings the port 6' into play instead of port 6. The connections of links R to valves M^2 may be simultaneously shifted to reverse the engine, by means of an annulus u, at 75 one side of the engine, to which annulus are pivotally connected links s which are 80 are connected also to the pivots connecting links Q-R. The annulus may be rotatably supported on lugs attached to the face of the engine, and as shown the annulus is 85 provided with guide slots v engaging such lugs and retained in position on the lugs by plates x, Fig. 10. The annulus may be 90 rotatably adjusted by means of a hand lever z, attached thereto at y, and when the annulus is in the position shown in full lines Fig. 10 the valves M^2 will be shifted so as to always direct the gases from the 95 exploding chambers through the ports 7 to the working chamber within the annulus. When the annulus is shifted to the position indicated by dotted lines z', Fig. 10, the valves M^2 will then direct the gases through 100 ports 7' to the working chamber. The cranks N and links Q-R are the means for 105 rocking the valves M^2 ; and the shafts H are rocked back and forth as described, by 110 the pistons so as to open and close ports 5 and 5' at the proper times. The working chamber is provided with four exhaust 115 ports 8, one of which is located intermediate each pair of adjacent ports 7, 7' so that the gases after operating the rotor can escape through ports 8 to any suitable exhaust pipe, (not shown).

Explosive gases are admitted into each end of each exploding chamber through pipes r, r', pipes r' being adjacent the rods F and pipes r adjacent rods F'; the adjacent pipes r, r' connect at different points 115 with a valve chamber L which may be mounted on the bracket I adjacent the arm G; and in each casing is a valve K having a radial port 20 which communicates at 120 center of the casing with a pipe 22, (see Figs. 7 and 8). The valve K is connected to the adjacent shaft H so as to be rocked thereby simultaneously with the shifting of the related valve M^2 , and valve K will alternately deliver the gas from pipe 22 to 125 the pipes r, r'. Gas is supplied to pipe 22 from a reservoir 41, Fig. 1, the supply from which may be regulated by a main controlling valve 42.

The explosive gases are supplied to the 130

reservoir 41 by means of a pump *d* which communicates with a pipe *f* leading from a suitable carbureter, (not shown,) and the explosive gases are drawn by the pump 5 through pipe *f* and forced through the pipe *e* into the reservoir 41. The pump *d* may be operated in any suitable manner. As shown in Fig. 1 the pump piston rod *e* is connected to a crank pin on a disk *e'* which is 10 rotatably mounted on a stud *e''* and is fast to a pinion *e'''* which meshes with a second pinion *e''''* on a stud, and pinion *e''''* in turn meshes with a pinion *e'''''* on shaft *a*, so that for each rotation of shaft *a* the pump may 15 be reciprocated a number of times. In Fig. 10 the pump piston rod *e* is shown as operated by an eccentric *b* on shaft *a*, so that it will be reciprocated once for each rotation of shaft *a*.

20 I do not confine myself to four explosive chambers as shown in the drawings; as there may be two, three, four, or more, as may be necessary to insure the proper operation of the valves, and obtain the desired power; 25 and said explosive chambers may be of any shape best adapted to the size of motor and to the use it is to be put. Also I do not wish to confine myself to any particular means for operating the pump; and the reservoir 30 41 might be supplied with explosive gases in any suitable way. The explosive gases admitted into the chambers 34, 35, 36, 37, may be ignited at the proper time by any suitable means; as shown I have indicated 35 an electrical spark plug *p* in each explosion chamber; and these spark plugs may be connected in any suitable way to any convenient source of electricity.

As shown each spark plug *p* is electrically 40 connected by a conductor *n* to contacts *o* beside the adjacent disks *J*; opposite each contact *o* is another contact *o'* which may be connected to a conductor *m*. The conductors *n* and *m* may be connected with opposite 45 poles of any suitable source of electrical energy. The conductors *n*, *m*, are similarly connected to contacts *o*, *o'* arranged beside the disk *J* at each end of each cylinder. On each disk *J* is a contact piece *N* which as the 50 disk is rocked, enters between the opposed contacts *o*, *o'* and closes the circuit therebetween, thereby transmitting current to the related spark plug and causing the ignition of the gases at the proper times.

55 The electrical connections are diagrammatically indicated in Fig. 6, but such connections constitute no part of the present invention, and may be varied according to the nature of the plugs used, or the preference 60 of the electrician, therefore it is unnecessary to give a more detailed explanation thereof herein.

27, 27' are check valves placed in the gas supply pipes *r*, *r'* to prevent gas being 65 forced back into the main supply pipe 22

at the time of ignition in the explosion chambers, and to relieve the pressure on the valves *K* and to help form the cushion 9.

70 Preferably the casing *A* is provided with communicating water chambers or passages 14, 14', 14'' around the chambers, ports and valves, and with water passages *j* in the walls of the cylinders *B*, *B'*, *B''*, *B'''*, so that they may be kept cool; the water may be introduced into these passages through 75 openings *g* on one side of the casing and withdrawn at *j* or any suitable point.

80 Operation: The compressed gas supplied from the reservoir 41 will force the pistons alternately from one end of the explosion chamber to the other when the throttle 42 is opened. Assuming that the gas has entered chamber 36, Fig. 2, at 5' under pressure from reservoir 41, it will push the piston 4' to the left, and such piston comes in contact with and forces the rod *F* to the left, operating the valve *K*, Fig. 10 attached to the related shaft *H*, and allowing the gas to enter the cylinder at 5; this will check the piston 4', but there is movement enough of 85 the rod *F* before the piston 4' is entirely stopped to also actuate the disk *J*, Fig. 10, and make the electrical connection at *N*, which explodes the gas in the cylinder 36, closing the port 5 and opening the port 5'; this action would necessarily retain the explosive gas in chamber 36, as the port 5' has to be opened by the like action of piston 4''' which will be moved in chamber 37 and actuate the related valve 6 so as to put port 5' in 90 communication with port 7. The several pistons all operate at about the same rate of speed and the explosions in the several chambers will necessarily occur in succession. After each piston has traveled in one 95 direction it will be moved back in like manner and operate the other valve, the rotor turning in the same direction. The explosive gases remain in the cylinders until the ports 7 or 7' are opened as described. In 100

initially starting the motor the pump *d* can be operated by hand (as by means of a crank (not shown) detachably attached to shaft *a*) until a sufficient supply of gas is compressed into the reservoir 41; or the reservoir 41 can be filled with compressed gas in any convenient manner. The motor will be self starting so long as there is a sufficient pressure of gas in the reservoir. Assuming that there is a proper supply of compressed gas 105 in reservoir 41, all that is necessary to start the motor is to open the throttle in the main gas supply pipe; this allows the gas (for example) to enter the explosion chamber 34 (Fig. 2) and force the piston head therein toward the right hand end of such explosion chamber where it comes into contact with the rod *F*, and forces it and the crank *G* to the right, thereby rocking the shaft *H* and the connected valve *K* so that the port 110 115 120 125 130

(Fig. 8) is opened, allowing gas to flow through pipe r' into that end of the explosion chamber and form a cushion between the piston and end of chamber such as shown at 9, chamber 36, Fig. 2. Such cushion prevents the piston from striking the cylinder head when the gas is exploded in the opposite end of the chamber, which explosion occurs as the contact n on the disk J , operated by said shaft H in its movement to the right, closes the circuit between the contacts o , o' , thus producing a spark at plug p , (Fig. 6) and an explosion in the chamber 34, Fig. 2. The exploded gas remains in the chamber 34 until the piston 4 in chamber 35 has forced the rod F therein down, thus operating the adjacent rock shaft and valve M^2 so that the port 5' in chamber 34 is opened to allow the exploded gas to pass from chamber 34 to the working chamber and operate the rotor in the direction indicated by the arrow and finally escape through the exhaust ports 8. This operation is repeated in succession in the four explosion chambers forcing the pistons in the directions indicated by the arrows. When the second piston has reached the opposite end of its explosion chamber and the valve M^2 at that point has been operated, the exploded gas in the first explosion chamber begins to flow through the ports; and the pressure is reduced in that end of such explosion chamber until the gas entering from the reservoir moves the piston in the opposite direction, thus exhausting all of the previously exploded gas. The pistons in each explosion chamber are thus operated and operate the rods F , F' , thus successively shifting the valves M^2 and allowing the exploded gases to pass through the ports 5, 6, 7, (Fig. 2) to the working chamber, and operate the rotor in the same direction. The explosions in the several chambers will necessarily follow each other in succession, as each is dependent upon the piston in the next following chamber to open the valve M^2 and allow the exploded gases to escape to the rotor; thus by the time the fourth piston has accomplished the operation of the valves the first piston is traveling in the opposite direction and the whole mechanism thereby becomes automatic. When the rotor rotates in the direction indicated by the arrows the ports 6 of the valves M^2 oscillate between ports 5 and 5' and the ports 7 remain open. To reverse the rotor the lever Z is thrown to the position indicated in dotted lines at z' , u' , and the connecting rods Q , R , to the dotted positions Q' , R' , thus shifting the valves M^2 closing ports 6 and causing the ports 6' to oscillate between ports 5 and 5'; thereby closing the ports 7, and opening the ports 7'; thus driving the rotor in a direction opposite to the arrows.

What I claim is:

65 1. An engine comprising a working cham-

ber, a rotor therein, a plurality of explosion chambers, ports to conduct the exploded gases from the explosion chambers to the working chamber, valves controlling adjacent ports of adjacent explosion chambers and adapted to retain the gases in the explosion chambers under compression, and means for automatically opening said valves after the explosions to permit the exploded gases to actuate the rotor. 70

2. In a motor, the combination of a working chamber, a rotor therein, a plurality of explosion chambers, adjacent ports for conducting gases from adjacent explosion chambers to different points in the working chamber; with single valves controlling adjacent ports whereby the gases may be directed through selected ports to the working chamber to cause the rotor to revolve in either direction desired. 80

3. In combination, a working chamber, a rotor therein, a plurality of explosion chambers, adjacent ports for conducting the exploded gases from adjacent explosion chambers to the working chamber; means for supplying gas to said explosion chambers, means for igniting the gases, and valves for controlling adjacent ports adapted to retain the gases in the explosion chambers under compression, and means for automatically actuating said valve to permit the exploded gases to pass to the working chamber. 90

4. In a motor, the combination of a working chamber, a rotor therein, a plurality of explosion chambers, adjacent ports for conducting gases from the explosion chambers to different parts of the working chamber; means for supplying gas to said explosion chambers, means for igniting the gases, and a single valve controlling the adjacent ports 100 whereby the gases may be directed through selected ports to the working chamber to cause the rotor to revolve in either direction desired. 105

5. In an engine, a working chamber, a plurality of exploding chambers adjacent the working chamber, ports for conducting exploded gases from the exploding chambers to the working chamber, valves for said ports, pistons in said working chambers, and means operated by said pistons controlling said valves. 110

6. In an engine, a working chamber; a plurality of exploding chambers adjacent the working chamber, ports for conducting gases from the exploding chambers to the working chamber, valves controlling the ports; pistons in said working chambers, and devices actuated by alternate pistons for operating the valves. 120

7. In an explosion engine, a working chamber, a plurality of exploding chambers adjacent the working chambers, ports for conducting gases from the exploding chambers to the working chambers, valves con- 125 130

- trolling the ports; unattached pistons in said working chamber, and devices operated alternately by pistons in adjacent working chambers for operating the valves.
5. 8. In a motor, a working chamber, a plurality of exploding chambers, pistons therein, ports connecting the working chamber with the exploding chambers, valves in said ports, rods projecting into the exploding chambers adapted to be engaged by the pistons, and means operated by said rods for actuating the valves.
10. 9. In a motor, a working chamber, a plurality of exploding chambers, pistons therein, rods projecting into the opposite ends of the explosion chambers, ports connecting the working chamber with the exploding chambers, valves in said ports, and means operated by said rods for actuating the valves, said rods being operated by the alternate action of pistons in the adjacent explosion chambers.
15. 10. In a motor, a working chamber, a plurality of exploding chambers, pistons therein, adjacent ports connecting the working chamber with adjacent exploding chambers, valves controlling adjacent ports, means operated by the pistons in the adjacent working chambers controlling the valves; electrical igniting devices in the exploding chambers, and circuit closing devices operated by the valve operating means, substantially as described.
20. 11. In an engine, a working chamber, a plurality of exploding chambers adjacent the working chamber, adjacent ports for conducting exploded gases from adjacent exploding chambers to the working chamber, valves controlling the adjacent ports, pistons in said exploding chambers, an igniting device in each exploding chamber, and ignition controlling devices operated by the valve actuating mechanism, substantially as described.
25. 12. In a motor, a working chamber, a plurality of exploding chambers, pistons therein, ports connecting the working chamber with the exploding chambers, valves in said ports, rods projecting into the explosion chambers adapted to be engaged by the pistons; means operated by said rods for actuating the valves, said rods being operated by the alternate action of pistons in adjacent explosion chambers; with igniting devices in the explosion chambers, and ignition controlling means operated by the valve actuating mechanism, substantially as described.
30. 13. In a motor, a working chamber, a plurality of explosion chambers adjacent the working chamber, a rotor in the working chamber, ports for conducting gases from the explosion chambers to the working chamber, valves controlling said ports, a rock shaft intermediate each pair of work-
- ing chambers, rods connected with said shaft and extending into the adjacent working chambers, pistons in said chambers adapted to engage said rods and rock the shaft, and connections between said shaft and the valves.
35. 14. In a motor, a working chamber, a plurality of explosion chambers around the working chamber, a rotor in the working chamber, ports for conducting gases from the explosion chambers to the working chamber; rocking valves controlling said ports; an oscillating shaft intermediate the adjacent ends of each pair of explosion chambers, rods connected with said shaft and projecting into the ends of such adjacent explosion chambers, unattached pistons in said chambers adapted to alternately engage said rods to rock the shaft, and connections between said shaft and the valves.
40. 15. In an engine, a working chamber, a plurality of explosion chambers adjacent the working chamber, adjacent ports for conducting gases from the explosion chambers to the working chamber, a single valve controlling the adjacent ports; pistons in said explosion chambers, and means controlled by said pistons for operating the valve, pipes for conducting explosive gases to the explosion chambers; valves controlling the admission of gas to said explosion chambers, and means for operating said gas controlling valves by and from the port valve operating means.
45. 16. In an engine, a working chamber, a plurality of explosion chambers adjacent the working chamber, ports for conducting gases from the explosion chambers to the working chamber, valves controlling the ports; unattached pistons in said explosion chambers, and devices actuated by said pistons alternately for operating the valve; a gas supply; pipes for conducting gases from said supply to the explosion chambers; valves controlling the admission of gas to said explosion chambers, said gas controlling valves being operated by the said port valve actuating devices.
50. 17. In a motor, a working chamber, a plurality of explosion chambers; pistons therein; rods projecting into the explosion chambers adapted to be engaged by the pistons, ports connecting the working chambers with the explosion chambers, valves for said ports; means operated by said rods for actuating the valves, said rods being operated by the alternate action of pistons in adjacent explosion chambers, means for conducting gases to the explosion chambers, valves controlling the admission of gas to said explosion chambers, said gas controlling valves being operated by the port controlling valve means.
55. 18. In a motor, the combination of a working chamber, a plurality of explosion

6
chambers adjacent the working chamber, a rotor in the working chamber, ports for conducting gases from the explosion chambers to the working chamber; valves controlling said ports, an oscillating shaft intermediate each pair of explosion chambers; rods connected with said shaft and projecting into the adjacent explosion chambers; pistons in said chambers adapted to engage said rods and rock the shaft; connections between said shaft and the valves for operating the latter; means for conducting gases to the explosion chambers; valves controlling the admission of gas to said chambers, said gas controlling valves being operated by said rock shafts.

19. The herein described engine comprising a working chamber, a rotor therein, a plurality of explosion chambers around the working chamber, a piston in each explosion chamber, a rock shaft intermediate each pair of explosion chambers, rods connected with said rock shaft and projecting into the adjacent explosion chambers and adapted to be actuated by the pistons therein, ports leading from the explosion chambers to the working chamber, valves in said ports, connections between said valves and said rock shafts, means for supplying explosive gases to the explosion chambers, and means for igniting said gases.

20. The herein described engine, comprising a working chamber, a rotor therein, a plurality of exploding chambers around the working chamber, a piston in each explosion chamber, a rock shaft intermediate each pair of explosion chambers, rods connected with said rock shaft and projecting into the adjacent working chamber and adapted to be actuated by the pistons therein; ports leading from the explosion chambers to the working chamber, valves in said ports, connections between said valves and said rock shafts, pipes conducting explosive gases to the explosion chambers; gas controlling valves for said pipes connected with and

actuated by said rock shafts; and means for igniting the gases in the explosion chambers.

21. In an engine, a working chamber, explosion chambers, adjacent ports for conducting gases from the explosion chambers to the working chamber; a single valve controlling the adjacent ports; pistons in the explosion chambers; means for admitting fresh gases into the explosion chambers to move the pistons therein in one direction, and means for igniting the gases after they have propelled the pistons the desired distance in the chambers.

22. In an engine, the combination of a working chamber, explosion chambers, adjacent ports for conducting burnt gases from the explosion chambers to the working chamber; a single valve controlling the adjacent ports, pistons in the explosion chambers; means for admitting fresh gases under pressure into the explosion chambers to move the pistons therein, and means for igniting the gases after they have propelled the pistons the desired distance.

23. In an engine, the combination of a working chamber, explosion chambers, ports for conducting burnt gases from the explosion chambers to the working chamber; valves for said ports, pistons in the explosion chambers; means for admitting fresh gases under pressure into the explosion chambers to move the pistons therein, and means for igniting the gases after they have propelled the pistons the desired distance; with rods projecting into opposite ends of the adjacent explosion chambers and adapted to be operated by the impact of the pistons therein, and means operated by said rods for actuating the valves.

In testimony that I claim the foregoing as my own, I affix my signature in presence of two witnesses.

ELMER E. E. SUTPHIN.

rection in Letters Patent No. 1,071,823.

Affidavit having been filed showing that the name of the patentee in Letters Patent No. 1,071,823, granted September 2, 1913, for an improvement in "Explosive-Engines," should have been written and printed *Elmer E. Sutphin* instead of "Elmer E. E. Sutphin" it is hereby certified that the proper corrections have been made in the files and records pertaining to the case in the Patent Office and should be read in the said Letters Patent that the same may conform thereto.

Signed and sealed this 21st day of October, A. D., 1913.

[SEAL.]

R. T. FRAZIER,

Acting Commissioner of Patents

6
chambers adjacent the working chamber, a rotor in the working chamber, ports for conducting gases from the explosion chambers to the working chamber; valves controlling said ports, an oscillating shaft intermediate each pair of explosion chambers; rods connected with said shaft and projecting into the adjacent explosion chambers; pistons in said chambers adapted to engage said rods and rock the shaft; connections between said shaft and the valves for operating the latter; means for conducting gases to the explosion chambers; valves controlling the admission of gas to said chambers, said gas controlling valves being operated by said rock shafts.

19. The herein described engine comprising a working chamber, a rotor therein, a plurality of explosion chambers around the working chamber, a piston in each explosion chamber, a rock shaft intermediate each pair of explosion chambers, rods connected with said rock shaft and projecting into the adjacent explosion chambers and adapted to be actuated by the pistons therein, ports leading from the explosion chambers to the working chamber, valves in said ports, connections between said valves and said rock shafts, means for supplying explosive gases to the explosion chambers, and means for igniting said gases.

20. The herein described engine, comprising a working chamber, a rotor therein, a plurality of exploding chambers around the working chamber, a piston in each explosion chamber, a rock shaft intermediate each pair of explosion chambers, rods connected with said rock shaft and projecting into the adjacent working chamber and adapted to be actuated by the pistons therein; ports leading from the explosion chambers to the working chamber, valves in said ports, connections between said valves and said rock shafts, pipes conducting explosive gases to the explosion chambers; gas controlling valves for said pipes connected with and

actuated by said rock shafts; and means for igniting the gases in the explosion chambers.

21. In an engine, a working chamber, explosion chambers, adjacent ports for conducting gases from the explosion chambers to the working chamber; a single valve controlling the adjacent ports; pistons in the explosion chambers; means for admitting fresh gases into the explosion chambers to move the pistons therein in one direction, and means for igniting the gases after they have propelled the pistons the desired distance in the chambers.

22. In an engine, the combination of a working chamber, explosion chambers, adjacent ports for conducting burnt gases from the explosion chambers to the working chamber; a single valve controlling the adjacent ports, pistons in the explosion chambers; means for admitting fresh gases under pressure into the explosion chambers to move the pistons therein, and means for igniting the gases after they have propelled the pistons the desired distance.

23. In an engine, the combination of a working chamber, explosion chambers, ports for conducting burnt gases from the explosion chambers to the working chamber; valves for said ports, pistons in the explosion chambers; means for admitting fresh gases under pressure into the explosion chambers to move the pistons therein, and means for igniting the gases after they have propelled the pistons the desired distance; with rods projecting into opposite ends of the adjacent explosion chambers and adapted to be operated by the impact of the pistons therein, and means operated by said rods for actuating the valves.

In testimony that I claim the foregoing as my own, I affix my signature in presence of two witnesses.

ELMER E. E. SUTPHIN.

Witnesses:

JOSEPH A. DANIEL,
THERESA M. WALTHER.

rection in Letters Patent No. 1,071,823.

Affidavit having been filed showing that the name of the patentee in Letters Patent No. 1,071,823, granted September 2, 1913, for an improvement in "Explosive-Engines," should have been written and printed *Elmer E. Sutphin* instead of "Elmer E. E. Sutphin" it is hereby certified that the proper corrections have been made in the files and records pertaining to the case in the Patent Office and should be read in the said Letters Patent that the same may conform thereto.

Signed and sealed this 21st day of October, A. D., 1913.

[SEAL.]

R. T. FRAZIER,

Acting Commissioner of Patents
